UNITED STATES PATENT OFFICE.

HENRY G. WURM, OF YONKERS, NEW YORK.

DESIGN FOR LEATHER, WALL-PAPER, OR SIMILAR ARTICLE OF MANUFACTURE.

59,880.

Specification for Design.

Patented Nov. 29, 1921.

Application filed August 2, 1921. Serial No. 489,393. Term of patent 7 years.

To all whom it may concern:

Be it known that I, HENRY G. WURM, a citizen of the United States of America, residing at Yonkers, in the county of Westchester and State of New York, have invented a new, original, and ornamental Design for Leather, Wall-Paper, or Similar Article of Manufacture, of which the following is a specification, reference being had to the drawing forming a part thereof.

The drawing shows a perspective of the design as applied to leather.

I claim:

The ornamental design for leather, wall paper or similar article of manufacture, as shown.

HENRY G. WURM.
